UNITED STATES PATENT OFFICE.

GEORGE M. MOULTON AND JOHN M. WITHERSPOON, OF CHICAGO, ILLINOIS.

GRAIN-BIN.

SPECIFICATION forming part of Letters Patent No. 732,102, dated June 30, 1903.

Application filed April 24, 1903. Serial No. 154,091. (No model.)

To all whom it may concern:

Be it known that we, GEORGE M. MOULTON and JOHN M. WITHERSPOON, citizens of the United States, residing at Chicago, in the 5 county of Cook and State of Illinois, have invented a certain new and useful Improvement in Grain-Bins, of which the following is a full, clear, concise, and exact description.

Our invention relates to cylindrical tile 10 grain-bins; and its object is to provide an improved structure which will possess great strength and afford complete protection to the contents against water or fire.

We will describe our invention by reference 15 to the accompanying drawings, wherein—

Figure 1 is a sectional plan view of a portion of the wall of a cylindrical grain-bin constructed in accordance with our invention. Fig. 2 is a detail view of a fragment of the 20 wall in perspective, showing how the parts are constructed and built up; and Fig. 3 is a detail perspective view of a single one of the tiles used in the construction.

The same letters of reference are used to designate 25 corresponding parts wherever shown.

It has been proposed heretofore to construct grain-bins of courses of straight and narrow hollow tiles arranged vertically and intermediate courses of horizontally-arranged shallow 30 trough-shaped tiles of lesser height with metal tension members embedded in cement in said trough-shaped tiles. Such construction has been found somewhat objectionable in that the vertical tiles afford only narrow edges for the application of the cement mortar at the joints, so that in a driving rain or continued wet weather the moisture could penetrate the thin walls and, running down the inside, find its way to the interior of the 35 bin, so causing damage to the grain within. Owing to the thinness of the material at the joints this structure was also somewhat lacking in strength and required special skill in its construction to apply the mortar thoroughly and evenly to the narrow vertical edges without allowing considerable quantities to fall down in the vertical hollows. A proposed remedy for these defects has been to provide sheets of wire-netting or metal 45 fabric interposed between the joints to assist in sustaining the mortar; but this expedient

besides being expensive has not been entirely effective to meet the objections above pointed out. A further objectionable feature of this construction is that in building up the wall 55 before the hardening of the mortar the smaller trough-shaped tiles would be easily displaced because of their lack of weight and their insecure seat upon the edges of the vertical tiles, this result being frequently brought about by the lateral thrust of the metal tension members when these latter did not conform exactly to the curvature of the tank and were slightly sprung or placed in the troughs under a stress. 65

In accordance with our invention the tiles *a a* instead of being set vertically on end are disposed horizontally with flat plane surfaces *a'* at top and bottom. These surfaces may, however, be scored or roughened to hold the 70 mortar more readily. The tiles are also preferably made curved to correspond to the curvature of the bin. The trough-tiles *b b* are preferably made of substantially the same external shape and dimensions as the other 75 tiles and are constructed with an intermediate horizontal cross-web *b'* a short distance below the top, forming the bottom of the trough. These tiles are also preferably provided with a strengthening-web *b''*, joining 80 said cross-web with the bottom wall of the tile. A considerable advantage arises from making the trough-tiles of large size and weight, corresponding to the other tiles, in that the wall may be more rapidly built and 85 the tiles are less likely to be displaced by the tension members or from other causes during construction.

The tension members *c c* are laid in the troughs, as usual, with cement mortar *d*, 90 packed in about them to the level of the top of the trough. Broad flat surfaces extending throughout the thickness of the wall are thus provided for the application of the mortar between each and every horizontal course 95 of tiles, making the structure of great strength, with the joints of such thickness that the passage of moisture through them is effectively prevented.

The tension members *c c* in each course of 100 trough-tiles *b* form, in effect, a continuous band or hoop extending entirely around the

bin and built into the wall thereof to strengthen it against bulging pressure from the inside.

We prefer to provide our grain-bins with 5 armor-tiles *e e*, applied to the outer walls, as shown.

Having thus described our invention, we claim—

1. A grain-bin having its walls built up of 10 courses of horizontally-disposed hollow tiles *a* having flat plane surfaces at top and bottom, intermediate courses of trough-tiles *b b*, tension members disposed in the troughs, and cement mortar packed around said tension 15 members and filling said troughs to the level of the top surfaces of said tiles, the top and bottom of each course of tiles being thus provided with continuous engaging surfaces for the mortar throughout the thickness of the 20 wall, whereby the wall is made solid along the horizontal joints.

2. A cylindrical grain-bin built up of courses of horizontally-disposed hollow tiles *a* having flat plane surfaces at top and bottom, and 25 intermediate courses of hollow trough-tiles *b* of substantially the same external form and dimensions as said tiles *a*, each of said trough-tiles being constructed with a horizontal intermediate web *b'* forming the bottom of the 30 trough, tension members *c* disposed in the annular troughs formed by said tiles *b*, and cement mortar packed around the tension members and filling said troughs to the level of the top surfaces of said tiles *b*, the top and 35 bottom of each course of tiles being thus provided with continuous engaging surfaces for the mortar throughout the thickness of the

wall, whereby the wall is made solid along the horizontal joints.

3. A fireproof cylindrical grain-bin built 40 up of courses of horizontally-disposed hollow curved tiles *a* having flat plane surfaces at the top and bottom, and intermediate courses of trough-tiles *b* of substantially the same external form and dimensions as said tiles *a*, 45 each of said trough-tiles being constructed with a horizontal intermediate web *b'* forming the bottom of the trough, and a supporting-web *b''* joining said horizontal web with the bottom of the tile, tension members *c* disposed in the annular troughs formed by said tiles *b*, and cement mortar packed in said troughs around the tension members.

4. A tile wall comprising courses of horizontally-arranged tiles *b*, each of said tiles 55 having a horizontal intermediate web forming the bottom of an open trough, the lower portion of the tile under said web being hollow, tension members *c* disposed in the said troughs, and cement mortar packed about 60 said tension members and filling said troughs to the level of the top surfaces of the tiles, the top and bottom of each course of tiles being provided with continuous engaging surfaces for the mortar throughout the thickness 65 of the wall, whereby the wall is made solid along the horizontal joints.

In witness whereof we hereunto subscribe our names this 20th day of April, A. D. 1903.

GEORGE M. MOULTON.
JOHN M. WITHERSPOON.
